Primary Examiner — Cynthia Underwood(74) Attorney, Agent, or Firm — Griffiths & Seaton PLLC;
JoAnn M. Seaton(57) CLAIM

The ornamental design for a bowl, as shown and described.

DESCRIPTION

FIG. 1 is a front, perspective view of a bowl showing a first embodiment of our new design;

FIG. 2 is a front view thereof, the rear view being identical to the front view;

FIG. 3 is a right side view thereof; the left side view being identical to the right side view;

FIG. 4 is a top view thereof; and

FIG. 5 is a bottom view thereof.

FIG. 6 is a front, perspective view of a BOWL showing a second embodiment of our new design showing unclaimed faux wood grain on outer surfaces thereof;

FIG. 7 is a front view thereof, the rear view being identical to the front view;

FIG. 8 is a right side view thereof; the left side view being identical to the right side view;

FIG. 9 is a top view thereof; and,

FIG. 10 is a bottom view thereof.

The broken lines in FIGS. 6-12 represent faux wood grain and form no part of the claim.

1 Claim, 8 Drawing Sheets(56)
